UNITED STATES PATENT OFFICE.

ROBERT B. MITCHELL, OF HILLSDALE, MICHIGAN.

DISHWASHING MACHINE.

Application filed October 8, 1921. Serial No. 506,382.

The object of this invention is to provide a dish washing machine for household or other use which will be self-contained, compact, portable, and adapted for economical operation. With these ends in view, the washer consists essentially of a tank suitably mounted for easy transport having within the tank a series of racks for the reception of dishes to be washed, together with spray heads for delivering the water upon the dishes under the action of a pump operated by means of a small electric motor. Provision is made for the continuous circulation of the water and for the removal of sediments or waste washed from the dishes as occasion may require.

Further objects will appear from a detailed description of the invention which consists in the features of construction and combinations of parts hereinafter described and claimed.

In the drawings:

Figure 1 is a sectional elevation of a washing machine, showing the spray heads and associated parts in elevation;

Fig. 2 is an enlarged sectional view of the exterior chamber and waste strainer;

Fig. 3 is a detail showing the arrangement of the three-way valve for controlling the flow of the water;

Fig. 4 is a sectional elevation of the three-way valve;

Fig. 5 is a top or plan view of the upper spray head;

Fig. 6 is a diagrammatic view showing the angular arrangement of the spray openings in the discharge head;

Fig. 7 is a detail partly in section showing the hub mountings for the spray head;

Fig. 8 is a sectional elevation of the exterior tank for silverware;

Fig. 9 is a horizontal section view of the same;

Fig. 10 is a diagram indicating the angle of impingement of the water against the plates stacked in the lower rack;

Fig. 11 is a plan view of the lower dish rack; and

Fig. 12 is a sectional elevation thereof.

50 The washer comprises a main tank 1 preferably of cylindrical shape provided with a conical bottom 2 having its apex to one side

of the center. The tank is mounted upon a plurality (preferably three) of legs or standards 3 which are provided with castors 4 to facilitate movement. The upper end of the tank is closed by means of a cover 5 secured at one side to a bracket hinge 6, and provided with a handle 5^a for lifting the cover. The cover is flanged around its periphery which fits into the mouth of the tank, and when lowered is supported by an annular inwardly extending bead 7 which also furnishes a support for an upper wire rack 8 for the reception of deep vessels, such as cups, tumblers, and the like.

Below the upper rack is located a lower rack 9 which finds support upon the periphery of the conical bottom, which rack is intended for the reception of plates, saucers, or other substantially flat dishes which are supported on edge at a slight angle to the vertical, as indicated in Fig. 10. The special construction of the wire racks will be hereinafter referred to.

The water for washing purposes is supplied through a fitting 10 in the form of a side hill flange which is entered through the center of the conical bottom and furnishes a support for a fixed upstanding water pipe 11 which, at its upper end, carries a rotatable hub 12 from which extend a set of short radial lower arms 13 and a set of long radial arms 14, which arrangement of hub and pipes constitute the spray head for delivering the water to the dishes. It will be noted that the spray head occupies an intermediate relation between the upper and lower dish racks, and the upper set of arms are designed to spray water both upwardly and downwardly while the lower set of arms discharge downwardly only.

The hub 12 and mounting therefor are best illustrated in Fig. 7, wherein it will be noted that the hub is provided at its ends with upper and lower socket heads 15 and 16 respectively, the former of which is in the form of a cap, and furnishes an upper discharge chamber 17, and the latter furnishes a lower discharge chamber 18 in communication with the upper and lower sets of radiating discharge pipes. The lower chamber communicates with the slot or orifice 19 in the side wall of the center

pipe, which latter extends to a point within close proximity to the upper end of the hub, which latter is closed at its upper end and provided with a centrally disposed boss 20 5 which contacts a stop bearing 21 for limiting the upward lift of the spray head under pressure of the water by contact with the center of the superimposed upper dish rack.

When the device is in operation, the hub 10 and associated parts will be lifted out of contact with the upper end of the supply pipe, as indicated in Fig. 7, so that the spray head will ride freely on a water cushion, thereby minimizing friction and avoiding 15 the necessity of using ball bearings or like anti-friction elements.

The water is discharged from the radiating arms in a manner now to be described. The upper arms, four in number, are equally 20 spaced, as shown in Fig. 5, and each arm is provided along its top center line with a series of equally spaced upper discharge ports 22, the corresponding ports on the several arms being arranged at varying distances 25 from the axial center of the spray head as shown in Figs. 5, 6 and 7, so that, as the spray head is rotated, the respective inner, intermediate and outer discharge ports will circumscribe circles of varying radii, thereby 30 serving to deliver jets of water to all parts of the upper portion of the tank, said jets being directed upwardly into the downwardly opening cups or other deep dishes.

The upper arms are also provided with 35 two sets of lower discharge ports, one set comprising ports 23 which are arranged in a line at an angle of about 15° from the vertical center of the arms, and the other set 24 standing in line at an angle of about 40 45° from the vertical center, as diagrammatically indicated in Fig. 6. The number of openings on each arm set at an angle of 45° is greater than the number of openings on each arm set at 15° . The corresponding sets 45 of ports on the several arms are arranged at varying distances from the axial center after the manner previously described with reference to the upper discharge ports. The lower ports are designed to discharge jets of 50 water at two distinct angles which is desirable in order to effect a thorough cleansing of both sides of the flat dishes supported in the lower dish rack.

Each of the lower short arms 13 is provided with two sets of similar ports arranged respectively at angles of 45° and 15° , the ports arranged 45° being greater in 55 number, and the placing of the sets of ports from the axial center varying in the respective arms in order to circumscribe a considerable number of concentric circles. All of the 45° ports on the upper and lower sets of arms are arranged on the same side thereof, so that, when water is discharged from 60 the upper and lower arms, the re-action of

the greater number of 45° ports will overpower the re-action of the lesser number of 15° ports causing the spray head, as a whole, to rotate in a given direction.

The water is educted from the tank 70 through an outlet pipe 25 which leads to a screen chamber 26 having a cover 27 provided with a handle 28. The cover has entered therethrough a rod 29 which connects with a cup-shaped screen 30 suspended from a frame 31 which rests upon a shoulder or ledge 32 in the screen chamber. The screen is provided to arrest waste or sediment, which latter can be removed by lifting the screen from the screen chamber and 80 washing it out as occasion may require. The chamber is of sufficient depth to accommodate the water level in the main tank, and by locating it in exterior relation thereto, it is easily accessible for cleaning. The lower end of the chamber has secured thereto an elbow 33 which connects with a return pipe 34 leading to a centrifugal pump 35, which latter is driven by an electric motor 36 through a flexible coupling 37. The pump 90 drives the water to the delivery pipe 11 through a pipe connection 38 provided with a three-way valve 39, which latter has connected thereto a hose 40 leading to a silverware tank 41, the connection between the hose and the tank being tangentially arranged, as indicated in Fig. 9; and the tank being provided in the center of its bottom with a small discharge outlet 42.

The three-way valve and associated parts is illustrated in Fig. 3, from which it will be seen that the valve plug is operated by means of an arm 43 to which a rod 44 is secured leading to a knob or handle 45 conveniently arranged for operation. The spring 46 is provided for maintaining the valve in either one of two positions in which communication is either established between the pump and the upstanding pipe 11 and cut off from the hose 40, or vice versa.

The construction of the lower wire dish rack will now be described. This rack consists of an upper section framed on an upper outer wire ring 43^a and an upper inner wire ring 44^a and a lower section framed on a lower outer wire ring 45^a, a first intermediate ring 46^a, a second intermediate ring 47, a third intermediate ring 48 and an inner lower ring 49. The upper and lower sections are held in spaced relationship by means of a plurality of spacing rods or wires 50 arranged an equal distance around the structure and connected at their upper and lower ends to the upper and lower outer rings respectively. This gives to the structure a drum shaped formation.

The inner upper ring 44^a provides an inner connection for a series of radiating rods 51 which in most cases are equally spaced and extend radially to a distance of 125 130

slightly more than one half the radius of the structure. The outer end of each radiating rod abuts against an obliquely arranged outer rod 52; the inner end of each of which rods terminates against the side of the next adjacent inner radiating rod with the exception that in some cases, as will appear from the upper right hand side of Fig. 11, two of the obliquely disposed rods 10 terminate upon the same radiating rod which has the effect of reducing the space subtended between adjacent obliquely disposed rods. At the left of Fig. 11 it will also be noted that the arrangement described is departed from for the purpose of providing enlarged spaces for the reception of large dishes. The obliquely disposed rods terminate upon the outer upper ring and in conjunction with the radiating rods 51 15 furnish an interconnection between the inner and outer rings thereby tending to rigidly reinforce the same and knit the whole into a unitary form.

The radiating inner rods have hung therefrom inner and outer pairs of connecting wires 53 and 54, each pair extending at a slight angle to the vertical, the lower ends 25 of the respective connecting wires being hooked under the underlying adjacent rings to afford obliquely upstanding fingers adapted to engage the lower edge of a plate saucer or the like to hold the same in place within the rack space afforded between adjacent radiating bars. The provision of these connecting rods also assists in reinforcing the structure. In like manner the obliquely disposed outer bars 52 are connected to the underlying rings by means of connecting bars 56 provided with hooked ends 57 similar to those previously described. This arrangement is one which affords a series of inner radially arranged compartments and a series of outer compartments angularly disposed with respect to the former, the outer compartments being longer than the inner compartments to accommodate flat plates or dishes of the larger sizes.

In order to furnish additional reinforcement, the bottom section is provided with 30 a plurality of base rods 58 which extend generally in a radial direction and cut across the series of rings composing the bottom section to which they are secured. In order to rigidly and permanently unite the rods and rings composing the rack, it is preferred to connect the same together by soldering, spot welding, or similar form of connection.

In operation, the tank cover is tilted back, 35 the upper rack removed and all the plates to be washed, including platters and frying pans, placed in the lower basket. The plates or other flat dishes are supported on edge in the holders provided therefor at the angle indicated in Fig. 10. This arrangement will cause the water discharged from the 45°

ports to impinge against the inner surfaces of the plates which are tilted forward to somewhat reduce the angle at which the 45° jets of water impinge, and at the same time the back surfaces of the plates will stand at 40 angular relation to the jets of the water discharged from the 15° ports, so that the plates will be thoroughly washed on both faces.

In placing the plates in position, it is 45 not necessary to remove the spray head as it can be easily swung out of the way in inserting the plates. After the latter are positioned, the upper rack is then placed in the tank and filled with all the deep dishes. Hot water containing a suitable washing compound is then poured into the machine, the cover being lowered when the electric motor starts. The amount of water provided need only be sufficient to feed the pump 50 and maintain a high temperature while washing. The water entering the spray head under the force of the pump is expelled through the discharge port into the upper and lower radial arms. The preponderant action of the water discharged through the large number of 45° openings causes the spray head to rotate, thus distributing the water in jets over all of the dishes both above and below the spray head. 55 The water discharged upwardly from the top openings in the upper set of arms shoots up into the deep dishes, the surplus striking the cover falling down on the outside of such dishes. The water in the tank 60 flows through the circulating system and back to the pump, passing meanwhile through the screen where all waste and scraps are collected for removal.

The silverware is placed in the exterior 65 tank 41 which is preferably located in the sink. When the motor has been run for two or three minutes, the three-way valve is shifted, thus shutting off the water supply through the main tank and directing the 70 water into the silverware tank. The water, under pressure, enters at a tangent near the bottom causing a swirling or vortical action, thus cleaning the silverware. The small drain opening 42 allows the water remaining in the vessel to run out into the sink. The cleaning water has now been all removed from the tank through the action of the pump, and the screen is then removed 75 and placed under a faucet to remove the 100 waste and scrap collected therein. After 105 cleansing, the screen is replaced, the tank cover tilted back and the rinsing water 110 poured over the dishes. After this the motor is again started and the dishes and silverware rinsed. The dishes and silverware 115 are then allowed to dry and removed, and the machine may be easily pushed back into a corner out of the way, thus completing the 120 operation.

The arrangement is one which effects a discharge of water under pressure to all portions of the tank to effect a thorough cleansing of the dishes. The arrangement 5 is such as to permit the dishes to be easily placed and in position to be removed, and the method of utilizing the discharge from the main tank for the purpose of cleaning the silverware not only effects a quick 10 emptying of the main tank in preparation of the rinsing operation, but serves to clean the silverware during the period of such discharge.

The device is compact in structure and 15 neat in appearance, and can be instantly set up and operated in any establishment where an electric current is provided.

I claim:

1. In a dish washing machine, the combination of a tank, upper and lower dish holders within the tank, a vertically disposed supply pipe, a pump for forcing water through the supply pipe, a hub rotatably mounted on the supply pipe, an upper set 25 of radiating arms carried by the hub and each provided with a set of upwardly discharging ports and a set of downwardly discharging ports, and a set of lower radiating arms carried by the hub and each provided 30 with downwardly discharging ports, both sets of arms being positioned to rotate in a plane intermediate the upper and lower dish 35 holders, substantially as described.

2. In a dish washing machine, in combination with a tank and holders for the dishes, a vertically disposed supply pipe, a pump for forcing water through the supply pipe, a hub rotatably mounted on the supply pipe, an upper set of radiating arms each 40 provided with a set of upwardly discharging ports and a set of downwardly discharging ports, and a set of lower radiating arms provided with downwardly discharging ports, the sets of downwardly discharging ports on 45 the upper and lower arms being arranged on each arm in two series of differing angular relation on opposite sides of the vertical center of each arm, the ports having the greater angular divergence from the vertical 50 being greater in number than the others in order to establish a preponderant re-acting force serving to rotate the spray head, substantially as described.

3. In a dish washing machine, in combination with a tank and holders for the dishes, a vertically disposed supply pipe, a pump for forcing water through the supply pipe, a hub rotatably mounted on the supply pipe, an upper set of radiating arms 55 each provided with a set of downwardly discharging ports, and a set of lower radiating arms provided with downwardly discharging ports, the sets of downwardly discharging ports on the upper and lower arms 60 being arranged on each arm in two series of 65

differing angular relation on opposite sides of the vertical center of each arm, the ports having the greater angular divergence from the vertical being greater in number than the others in order to establish a preponderant re-acting force serving to rotate the spray head, substantially as described. 70

4. In a dish washing machine, the combination of a tank, a vertical supply pipe within the tank for supplying water under pressure, a hub rotatably mounted on the supply pipe, a set of relatively long upper tubular arms radiating from the hub, a set of relatively short tubular lower arms radiating from the hub, the upper arms being provided with a series of upwardly discharging ports and two series of downwardly discharging ports, one of the latter series comprising a greater number of ports arranged at a greater angle of divergence from the vertical than the ports comprising the other series, the lower set of short radiating arms being provided with two series of ports, the series comprising the greater number of ports being arranged at a greater angular 85 divergence from the vertical than the ports comprising the other series, and upper and lower dish racks respectively above and below the radiating arms, substantially as described. 90

5. In a dish washing machine, the combination of a tank, a spraying apparatus within the tank, a supply pipe for the spraying apparatus having interposed therein a three-way valve, a pump for the supply pipe, a return pipe leading from the tank back to the pump, an exterior receptacle for silverware, and a pipe leading from the three-way valve to the exterior receptacle and connected thereto in tangential relation, the three-way valve affording means for cutting off the supply of water to the main tank and directing the water flowing from the main tank through the pump to the exterior receptacle, substantially as described. 100

6. In a dish washing machine, in combination with a tank, a vertical supply pipe for supplying water under pressure thereto, a hub surrounding the upper end of the supply pipe, said hub being closed at its upper end and provided with an annular chamber near its lower end, and the pipe contiguous to the annular chamber being perforated to supply water to the chamber, upper and lower sets of tubular arms radiating from the hub, the lower set communicating with the annular chamber, and the upper set with the space adjacent the upper end of the supply pipe, the tubular arms being provided with discharge ports rearwardly directed with respect to the direction of intended rotation, and the hub and tubular arm being vertically movable upon the pipe, substantially as described. 115

7. In a dish washing machine, in combina- 120

tion with a tank, a vertically disposed supply pipe within the tank for supplying water under pressure, a hub rotatably mounted and freely resting upon the upper end of the supply pipe and vertically movable with respect thereto, and a series of tubular spray arms radiating from the hub and opening

thereinto at a point adjacent the upper end of the supply pipe, the said arms being provided with discharge ports rearwardly directed with respect to the direction of intended rotation, substantially as described.

R. B. MITCHELL.
